UNITED STATES PATENT OFFICE

WILLIAM E. CODDO, OF CHICAGO, ILLINOIS

SHAVING-BRUSH ATTACHMENT

Application filed September 2, 1927. Serial No. 217,195.

This invention relates to certain novel improvements in a shaving brush attachment and more particularly to a styptic pencil adapted for attachment to the handle of a shaving brush and has for its principal object the provision of an improved construction of this character which will be highly efficient in use and economical in manufacture.

Among the salient objects of the invention 10 is to provide a simple arrangement of parts for associating a styptic pencil with a shaving brush.

Other objects will appear hereinafter.

The invention consists in the novel combination and arrangement of parts hereinafter described and claimed.

The invention will be best understood by reference to the accompanying drawing, showing the preferred form of construction, 20 and in which:

Fig. 1 is a longitudinal cross-sectional detail view of the invention.

Fig. 2 is a longitudinal cross-sectional detail view of the invention showing a modified 25 form of construction.

Fig. 3 is a longitudinal cross-sectional detail view of the invention showing a still further modified form of construction.

Fig. 4 is a typical side elevation view of a 30 styptic pencil, embodied in the invention.

Fig. 5 is a fragmentary cross-sectional detail view of the invention showing a still further modified form of construction; and

Fig. 6 is a sectional detail view taken substantially on line 6—6 of Fig. 1.

Styptic pencils, with which I am familiar, prior to my invention are sold to the buying public apart from the shaving brush and the user of the styptic pencil ordinarily is careless 40 in placing the same away when not in use and often the styptic pencil when not in use comes into contact with moist articles or the like and is greatly deteriorated in its value. In addition to this, the styptic pencil not being a part of the shaving brush is easily 45 lost or misplaced when not in use. It is therefore one of the many objects of this invention to provide a simple arrangement of parts for 50 associating the styptic pencil with a shaving brush whereby to afford convenient use there-

of and to protect the same from dampness or the like.

To accomplish this and other objects of the invention, I have shown in Fig. 1 a shaving brush 10 which includes a handle portion 11 carrying the usual bristles 12. This handle 11 in the present instance has formed therein a hollow compartment 13 and the open end of this compartment is closed by a cap 14 secured in closing position through the medium of a bayonet and slot connection 15. The cap 14 has formed therein a socket 16 threaded as at 17 to receive a plug 18. Formed as an integral part of this plug 18 are radially disposed fingers 19 having the upper end portions 20 slightly curved outwardly to provide guiding surfaces 21. The styptic pencil is indicated at 22 and is associated with the plug 18 by mounting the end portion 23 thereof between the fingers 19, which fingers 19 are preferably of a yieldable structure whereby to frictionally hold the styptic pencil.

When the styptic pencil is not in use the same is confined in compartment 13 and to use the styptic pencil it is only necessary 75 to detach the cap 14 from connection with the handle 11.

While I have illustrated a bayonet and slot connection for the cap 14, it is manifest that the cap may be threaded into the compartment without departing from the spirit of the invention.

In Fig. 2 I have illustrated a modified form of construction and in this form of construction the cap 14' defines an annular flange 15' adapted to fit into a recess 16' formed in the handle 17'. The edge 18' of the flange 15' is tapered outwardly from the cap 14' a sufficient distance for snapping engagement in the recess 16'. The styptic pencil 22 is associated with the cap 14' by mounting the end portion 19' between the fingers 20' formed as an integral part of a holder 21' connected to the cap 14' through the medium of a screw element 22'.

This structure is extremely simple and affords expeditious association of the styptic pencil with the shaving brush.

In Fig. 3 a still further modified form of construction is shown and this form embodies 100

a handle 24 providing a compartment 25. Closing this compartment 25 is a cap 26 and this cap 26 may be connected to the handle 24 in any approved manner such as is illustrated in Fig. 6. The styptic pencil holder is indicated at 27 and includes a body defining the yieldable fingers 28 which engage the end portion 29 of the pencil. The outer lower surfaces of these fingers 28 have formed thereon threads 30 adapted for threaded engagement with the interior threads 31 of the sleeve 32. The end portion 33 of this sleeve 32 is threaded into a socket 34 formed in the cap 26. The sleeve 32 has its upper end beveled inwardly to act upon a collar 32^a carried by the fingers 28 for wedging the fingers against the pencil.

To assemble the parts thus described, the styptic pencil 22 is mounted with its end portion 29 between the fingers 28. The holder 27 is then threaded into the sleeve 32 after which the sleeve is threaded into the cap 26 and when the pencil is not in use the cap 26 is detachably secured to the handle 24.

In Fig. 5 a still further modified form of construction is shown and in this form of construction the handle 35 provides an annular flange 36 within the compartment 37. Adjacent this open end portion and the threaded surface 38 of this flange is wedge-shaped for threaded engagement with the wedge element 39 formed as an integral part of the yieldable fingers 40 of the holder 41 which holder in the present instance provides an integral screw stud 42 threaded into the cap 43. In assembling these parts the pencil 22 is mounted with its end portion between the fingers 40. The holder is then threaded into the compartment and by reason of the wedge-shaped element 39 and tapered walls 38 the fingers will be yieldably pressed against this end portion of the pencil to removably hold the same in position in the holder.

The pencil if desired may have this end portion, which fits between the yieldable fingers, covered with tinfoil 44 or the like.

It will be apparent from the description herein set forth that I provide a simple arrangement for detachably associating a styptic pencil or the like with a shaving brush handle.

In use, when the pencil has been worn beyond use the same may be removed and a new pencil substituted therefor.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention what I claim as new and desire to protect by Letters Patent is:

1. In combination, a shaving brush including a handle having a hollow interior opening outwardly from one end portion of the handle, a cap closing the end portion of said handle, a holder secured to said cap and having a plurality of yieldable fingers adapted for engagement with an end portion of the styptic pencil, means for detachably connecting said holder to said handle when said cap is connected to said handle, and means for connecting said cap to said handle. 70 75

2. In combination, a shaving brush including a handle having a hollow interior opening outwardly from one end portion of the handle, a cap closing said open end portion of said handle, said cap having an inwardly opening screw-threaded socket formed therein, an open end sleeve having a screw-threaded base mounted in said socket, said sleeve having a screw-threaded portion formed interiorly thereof, a member having a base portion mounted in said screw-threaded portion and including yieldable fingers extending inwardly along said sleeve adapted to receive the styptic pencil, and means in said sleeve adapted to force said fingers into engagement with said pencil. 80 85 90 95

In testimony whereof I affix my signature.

WILLIAM E. CODDO.
